[57] CLAIM

I claim the ornamental design for a bottle, as shown and described.

DESCRIPTION

FIG. 1 is a perspective view of the bottle in accordance with the invention;

FIG. 2 is a side elevational view of the invention; the front, rear and opposite elevation views of the invention are identical; and,

FIG. 3 is a top plan view of the invention.

The bottom of the bottle is flat and unornamented. The broken lines in FIGS. 1 and 2 are for illustrative purposes only and do not form part of the claimed design.
